IMPULSE TYPE ROTARY CRUSHER

Hyosuke Sakurai, Chita District, Japan

Application February 4, 1937, Serial No. 123,956

5 Claims. (Cl. 83—11)

My invention relates to improvements in impulse type rotary crushers and more particularly to an improved construction and arrangement of working parts, and has for its object the provision of an improved rotary crusher most suitable for obtaining desirable fine powders at higher efficiency with less danger of breaking the working parts.

For a better understanding of my invention reference is taken to the accompanying drawings, in which Fig. 1 is a sectional side elevation of a rotary crusher embodying my invention; Fig. 2 is an elevation partly in section of Fig. 1; Fig. 3 is an enlarged sectional view of a detailed portion; Fig. 4 is a front view of the rotary disc; Fig. 5 is a partial sectional view of the stationary disc and Fig. 6 is a perspective view of stationary bars formed into a cage.

Referring to the drawings, 1 represents the casing of the crusher; 2 are side covers; 3 represents a bracket for supporting the rotor shaft 4 having a pulley 5 secured to it; 6 represents inlet passages leading to the rotor chamber and 7 is a hopper for receiving the material to be crushed. In accordance with this invention a rotor disc 8 secured to the shaft 4 is provided with a number of pins 9 projecting on both sides of the disc. These pins are arranged on concentric circles and on spiral curves α , each pin having the cutting edge 10 located in the direction of rotation. To the end covers 2 are secured series of stationary bars 11 arranged on concentric circles and projecting in the spaces between and adjacent to the revolving pins 9 secured to the rotor 8. The stationary bars 11 have angular cross-section and those bars 11 arranged on the same circle are cast integrally with end rings 11' just like a squirrel cage and the cage is secured by means of set screws 12 to the disc 13. Thus the rotor pins 9 projecting from the rotor disc 8 on both sides pass through the spaces between the cage bars 11 and also adjacent thereto as shown in Fig. 3. The stationary disc 13 is also provided with radially disposed ribs or teeth 14 on its inner surface. 15 is a cylindrical drum or screen surrounding the rotor and is made of a perforated plate or wire gauze. The perforated plate or wire gauze 15 is secured to the side rings 16 which are connected together by means of screw rods 17.

The hopper 7 is provided with adjustable gates 18 which are regulated by a handle 19 through suitable gearing. 20 is a tiltable bottom supported on a pivot 21 and operated by link mechanism 22 which is connected to an eccentric disc or cam 23 on a side shaft 24. The side shaft 24 may be

driven from the rotor shaft 4 through the gearing 25 and 26. In the passages 6 communicating between the bottom opening of the hopper and the inlet openings provided for the side covers and leading into the rotor chamber, are provided magnetic separators 27 which may consist of permanent bar magnets 28 secured to a removable disc. The magnetic separator 27 projects into the passage 6 and is used for removing magnetic substances mixed in the material to be crushed.

29 is an air inlet opening leading to the inlet passages 6, and 30 represents an exhaust opening provided for the casing 1 serving also as a delivery opening, and 31 is a delivery opening of the crushed material or air containing pulverized material.

The operation of the rotary crusher as above described is as follows: The materials to be crushed such, for instance, as dried fishes are put in the hopper 7 and the machine is driven by a suitable prime mover such as an electric motor, not shown. The adjustable gates of the hopper are opened and the bottom 21 is tilted and oscillated to-and-fro so that the materials may be delivered into the passages 6 alternately. If some magnetic materials such as nails or iron pieces are mixed in the materials they are attracted by the magnetic separator 28 so that the danger of breaking the crusher by the iron pieces can be avoided. The material introduced into the rotor chamber is thrown outwardly by the centrifugal force of the high speed rotor disc 8 and is torn, crushed and ground by the co-operation of the running pins 9 and the stationary bars 11 as well as the teeth 14. The angular edges of pins 9 and bars 11 effect cutting action for fibrous materials and the cut or crushed pieces are impinged against the stationary bars and are beaten by the revolving pins in rapid repetitions.

When the material is crushed into desired small pieces or fine powders sufficiently to pass through the perforated plate or screen 15, they are delivered through the opening 31 together with the air blast or collected into a box at the bottom of the casing. The air may be sucked from the inlet opening 29 into the rotor chamber of the crusher and the excessive air may be exhausted from the opening 30 in order to relieve the excessive high pressure in the casing.

The crushed powder may be sucked out by a fan through the opening 31 or may be collected in the bottom casing and then conveyed to a desired place. In this case the opening 30 should be closed by means of a valve. The delivery opening 31 of the casing may be connected with the

suction opening for the purpose of subjecting repeated crushing actions to the material.

The cage-like construction of stationary bars prevents the bending of each bar and provides very rigid cutting and crushing edges.

I claim:

1. A rotary impulse crusher comprising, in combination, an enclosing casing having an air intake port arranged substantially in the central plane of the casing and at the upper portion thereof and two inlet passages for raw materials arranged symmetrically on opposite sides of said air intake port and communicating therewith, a shaft rotatably mounted within said casing below said material inlet passages, a disk carried by said shaft, a plurality of pins extending axially from each face of said disk, the pins on each face being arranged in a plurality of concentric circles and the pins of adjacent circles being so disposed with respect to each other as to provide a series of spiral rows of pins converging toward the shaft, each of said pins being provided with a cutting edge on the free end thereof and with a second cutting edge on the longitudinal side thereof in the direction of rotation of the disk, a plurality of radially extending alternating grooves and projections on the walls of the casing on both sides of said disk and being in close proximity to the free ends of the pins carried thereby, a plurality of stationary bars attached to said casing and extending axially of said rotor disk, and being arranged in concentric, circular series, the bars of each circular series extending between adjacent circular series of pins carried

by said disk and having cutting edges formed thereon which cooperate with the cutting edges on the longitudinal sides of said pins, screening means surrounding the grinding assembly, and a single discharge means for crushed and screened material arranged substantially in the central plane of the casing.

2. A rotary impulse crusher according to claim 1, in which the alternate series of radially-extending projections and grooves are formed in annular plates which are attached to the casing on opposite sides of the disk.

3. A rotary impulse crusher according to claim 1, in which the stationary bars of each circular series are attached at their opposite ends to annular spacing and supporting rings, thereby providing a squirrel-cage structure.

4. A rotary impulse crusher according to claim 1, in which the stationary bars of each circular series are attached at their opposite ends to annular spacing and supporting rings to form a squirrel-cage structure, one of said rings of each such structure being attached to the wall of the casing.

5. A rotary impulse crusher according to claim 1, in which a hopper is provided at the upper portion of the casing to receive raw materials, said hopper communicating with said casing through said two inlet passages for raw materials, a tilttable bottom disposed between said hopper and said inlet passages, and means for operating said tilttable bottom to selectively open or close said passages.

HYOSUKE SAKURAI.
